UNITED STATES PATENT OFFICE.

GRANT HAMMOND, OF HARTFORD, CONNECTICUT, ASSIGNOR OF ONE-THIRD TO ALVA C. WASHBURNE, OF PITTSFIELD, MASSACHUSETTS; AND ONE-THIRD TO FREDERICK G. CRANE, OF DALTON, MASSACHUSETTS.

FIREARM.

1,140,512.

Specification of Letters Patent Patented May 25, 1915.

Application filed March 17, 1914. Serial No. 825,248.

To all whom it may concern:

Be it known that I, GRANT HAMMOND, a citizen of the United States, and a resident of Hartford, in the county of Hartford and State of Connecticut, have invented a new and Improved Firearm, of which the following is a specification:

My invention relates more especially to that class of firearms that are adapted to be discharged from the hand, and usually without other support, and an object of my invention, among others, is to provide a device of this class that shall be extremely simple in its construction, both as to form, arrangement and number of parts, and one that shall be particularly efficient in its operation.

One form of device embodying my invention, and in the construction and use of which the objects hereinabove set out, as well as others, may be attained, is illustrated in the accompanying drawings, in which—

Figure 1 is a view in side elevation of a firearm embodying my invention. Fig. 2 is a view in side elevation of the firearm with parts broken and cut away generally in central section to show construction, the breech-bolt, however, being cut on a plane located just at one side of the center. Fig. 3 is a view in section through the handle on plane 3—3 of Fig. 2. Fig. 4 is a view of the firearm looking at the side opposite to that shown in Fig. 2, the grip being removed and the parts broken away to show construction, the magazine also being removed. Fig. 5 is a detail view on plane 5—5 of Fig. 4. Fig. 6 is a side view of the magazine partly broken away to show construction. Fig. 7 is an edge view of the same. Fig. 8 illustrates a top, side, and end view of the breech-bolt. Fig. 9 is a detail view showing the relative positions of the hammer and breech-bolt when the latter is at the backward limit of its play. Fig. 10 is a fragmentary view, scale enlarged, illustrating the resistance block and its spring.

In the accompanying drawings, the numeral 15 denotes the handle or frame of my improved firearm and 16 the receiver constituting the upper part of the structure; the receiver and handle being formed integral each with the other. A barrel 17 is secured to the receiver in any suitable manner, and a

trigger guard 18 extends from the frame and within which a pivotally mounted trigger 19 projects.

A breech-bolt 20 is mounted in a breech-bolt chamber 21 in the receiver, this chamber having a discharge opening 22 through the top wall of the receiver through which the empty shells are discharged. The breech-bolt is of peculiar shape, being cut away more or less at the lower part but generally of a shape at its front end to fit the cylindrical bore constituting a portion of the breech-bolt chamber 21 in the receiver. This generally round portion constitutes the body 23 of the breech-bolt having an extension 24, generally of rectangular form in cross section and located at the upper part 70 of the breech-bolt, this extension being of a width to permit it to pass through a slot 25 in the receiver and within which the hammer 26 moves. Grooves 27 are formed in the bottom of the breech-bolt, extending longitudinally thereof and to receive projections from a magazine in a manner and for a purpose to be hereinafter described. A firing pin 28 is located in the breech-bolt at the top and a little at one side of the center in a position to strike the rim of a cartridge shell, the firing pin being held normally in a backward position by a spring 29 located in a spring chamber in the breech-bolt, said spring thrusting against a shoulder formed by an enlargement 30 on the firing pin, the spring chamber being closed by a tubular plug 31 through which the back end of the firing pin passes in position to be struck by the hammer 26. The enlargement of the firing pin is flattened on one side against which flattened part a guide pin 32 rests, this construction being for the purpose of holding the firing pin against turning movement. An extractor 33 is also located in a chamber 95 in the breech-bolt, the forward end of the extractor having a hook to engage the rim of a cartridge shell in the usual manner, the end of the extractor being beveled as shown in Fig. 8 so that it will ride over the rim of 100 the cartridge shell and engage said rim by the spring action of the extractor, and within a recess 34 in the end of the barrel.

The hammer 26 is pivotally mounted in the receiver in any ordinary manner, a spring rod 35 hooking over a pin in a recess

36 in the hammer, as shown in dotted outline in Fig. 2. The lower end of this rod projects into a headed sleeve 37, within which it is secured, as by means of a pin 38, a main spring 39 thrusting with one end against the shoulder formed by the head on said sleeve and the other end of the spring being located within and thrusting against a cap 40, said sleeve and cap being located in a well 41 formed in the handle of the firearm. A supporting plate 42 is secured to the outside of the handle 15, the upper end of the plate having a slot within which a breech-bolt actuating lever 43 is pivotally mounted, the upper end of this lever passing into a lever recess 44 in the breech-bolt. This lever is widened at its lower end, one wing having a breech closing lug 45 resting upon a breech closing block 46 secured to the cap 40. The lower end of this breech closing block is beveled, as shown in Fig. 3 of the drawings, and it rests against a correspondingly beveled surface at the upper end of a resistance block 47 loosely supported on a pin 48 secured to the plate 42. The angle of the beveled contacting surfaces of the breech closing block and resistance block is such that a sufficient force will cause them to disengage, the resistance block being moved outwardly under the thrust of the block 46, the mount of the resistance block upon the pin 48 being loose enough to permit this movement. A resistance spring 49 is secured to the resistance block and thrusts with its lower end against the inner surface of the supporting plate 42.

An opening lever 50 is pivotally mounted on the handle, its end being formed into a finger piece 51 underlying the trigger guard and in position to be readily actuated by the fingers. The heel of this lever is located in line with a wing 52 of the lever 43, and this heel is pivotally connected with a releasing bar 53 slidably mounted in the slot in the supporting plate 42, this bar having a beveled end 54 to engage behind the resistance block and move it from engagement with the block 46. A spring 55 secured to the supporting plate 42 thrusts against a shoulder on the releasing bar and tends to hold it normally disengaged from the resistance block. It will be noted that pressure of the resistance block 47 against the beveled surface 54 will secure this same result. It will be noted from this construction that pressure upon the finger piece 51 will move the releasing bar to disengage the resistance block from the breech closing block and a continued movement will engage the lever 50 with the wing 52 of the breech-bolt actuating lever and swing said lever on its pivot to move the breech-bolt backward and open the breech-bolt chamber.

65 A magazine 56 is constructed for location in the magazine chamber 57, the upper end of this magazine having prongs 58 to extend into the grooves 27 in the breech-bolt, these prongs acting as ejectors, the ends of the shells as they are drawn backward by the extractor striking these prongs thus causing the shells to be ejected through the discharge opening 22. The follower 59 of the magazine is supported upon a spring 60 arranged within the magazine in a well known manner. A feature of my improvement resides in the construction of this follower 59 so that it may yield and accommodate itself to the different angular positions of the cartridges which will vary according to the number of cartridges in the magazine. In my improved device the follower 59 is formed integral with a guide 61 resting against an upright edge wall of the magazine, the whole being of such construction that the follower 59 may yield, or assume different angular positions with respect to the guide 61. The upper front edges of the magazine chamber have a grooved lip 62 to guide and direct the cartridges as they are forced from the magazine by the nose 63 on the breech-bolt.

A sear 64 is mounted in the receiver in position for its end to engage a notch in the hammer and hold the latter against movement. A spring pressed pin 65 in the back of the sear thrusts against the spring rod 35 that is rigid enough to hold the sear normally in a position to engage the notch in the hammer. A sear actuating bar 66 is slidably mounted in the frame, its front end resting behind and against the trigger 19. A projection 67 is formed on the bar 66 to engage the sear and move it from engagement with the hammer. A cam notch 71 is formed in the bar to receive the end of an actuating pin 72 seated upon a spring that presses it against the bar. As the trigger, and consequently the bar, are moved backward the cam 68 on the bar, engaging with the cam 69 at the edge of the magazine chamber, will cause the projection 67 to be disengaged from the sear after the latter has been disengaged from the hammer, and when pressure upon the trigger is released, the spring pressed pin 72 acting upon the cam surface of the notch 71 will move the bar forward and cause it to normally rest against the trigger. Movement of the projection 67 out of line of movement of the sear enables the latter to swing so that it may engage the notch in the hammer should the latter be thrown backward while pressure upon the trigger is maintained. This construction will prevent unintentional repeated discharge of the firearm.

The sear is held against swinging movement in one direction by the front wall of the recess in which it is located, the lower end of the sear engaging such wall. It will be noted that the pivots of the sear and

hammer are so located and the point of the sear and notch in the hammer so relatively arranged that any force on the hammer tending to move it to firing position will 5 move the notch nearer the point of the sear, and this will also tend to move the sear to more closely engage the notch, and this arrangement guards against accidental firing by reason of blows inadvertently delivered 10 upon the hammer. An adjusting screw 70 is located in the back of the magazine chamber in position to engage the front part of the sear whereby the latter may be positioned to determine the extent to which it 15 will engage the notch in the hammer. By means of this screw the engagement of the sear and hammer may be so regulated that the firearm may embody the principles of a hair trigger, or one in which an incon- 20 siderable amount of pressure will be required to disengage the sear from the hammer. It will be noted that the rod 35 serves a double purpose, that of a sear stop as well as for a connection between the hammer and 25 main spring. The breech closing and resistance blocks retard the opening movement of the breech-bolt under the force of the gases for a sufficient period to enable the bullet to leave the barrel, after which this 30 force will have been exerted sufficiently to disengage said blocks and permit the breech-bolt to open.

The cartridges, as they rest in the magazine with the flanges of each out of line 35 with the flanges of those on opposite sides, assume different angular positions, so that the pile as a whole takes a more or less curved form. In order to provide for this curved form of the pile I give to the magazine a more or less curved form by providing depressions 73 located in opposite edges of the magazine and out of line each with another. The spring rod 35 is preferably made of piano wire and has such resilient qualities that it will readily accommodate itself to the different positions of the pin on the hammer to which it is attached. The opening lever 50 is composed of comparatively thin metal, and in order to 40 impart rigidity to it and reduce the spring action between its sides, I mount the lever upon a pin 74 of angular shape in cross section so that the sides of the lever are prevented from relative turning movement.

55 It will be noted, as shown in Fig. 9 of the drawing, that the hammer is so mounted that when it is cocked and the breech-bolt is at the backward limit of its play, its end will be substantially on a vertical plane co- 60 incident with the back of the hammer, that is, the breech-bolt in its backward position does not project back of the hammer, and the objections incident to firearms in which the recoil slide in its backward movement 65 passes beyond the hammer are avoided. In

accomplishing this result I so construct the breech-bolt and mount the hammer that the latter strikes within the receiver, the back end of the breech-bolt in the forward position of the latter being located well within 70 the receiver and at some distance from its back end.

In order to aid in retarding the backward or opening movement of the breech-bolt for a time sufficient to prevent the gases 75 of explosion from passing out at the breech, in addition to the devices hereinbefore described I employ the following construction: An annular groove 75 is formed in the barrel in position to be covered by the cartridge shell when in place in the barrel. This groove will be of a depth depending upon the amount of resistance it is desired to impart to the removal of the cartridge shell, and this will depend upon the conditions with respect to the length of the shell 80 and the length of the barrel, the longer the barrel and the shorter the shell, the deeper will be the groove. As an example, with a six inch barrel, and what is known as a 85 "short" shell, that is a "22 rim fire", the depth of the groove would be approximately 5/1000 of an inch, it being understood that this is an approximate measurement given simply for the purpose of illustration. With 90 this construction the force of the gases within the shell expand its walls into the groove, and as a consequence more force is then required to move the cartridge shell from the breech with a result that the opening of the 100 breech action is delayed. This groove also acts to retard the opening movement of the breech action by affording a space within which the gases may expand before pressure is exerted backwardly against the shell and 105 the breech-bolt. This expanding action is aided by the mechanism within the handle hereinbefore described for retarding the opening movement of the breech action, in that the delay caused by this mechanism 110 allows the wall of the cartridge to be fully expanded into the groove before any backward movement of the shell takes place.

I claim—

1. A firearm including a breech-bolt, a 115 hammer, a spiral spring, a rod extending from the hammer through said spring and connected to the latter to receive its force, a member resting upon said spring, connections between said member and the breech-bolt to impart the force of said spring to the bolt, and means for controlling the movement of the hammer.

2. A firearm including a breech-bolt, a 125 hammer, a breech-bolt actuating lever, a spiral spring located in the handle of the firearm, a cap fitting over the top of said spring, a lug from said lever to receive thrust upon said cap, a rod resisting the force of the spring at its lower end, said 130

- 4 rod being connected with the hammer, and means for controlling the movement of the hammer.
- 5 3. A firearm including a handle having a well extending lengthwise therein, a main spring located in said well, a headed sleeve located in said well and upon which said spring rests, a hammer, a rod connecting said sleeve and hammer, a cap fitting over 10 the upper end of the spring, a breech-bolt, a breech-bolt actuating lever connected with the breech-bolt, a lug upon the lever overlying said cap, and means for controlling the movement of the hammer.
- 15 4. A firearm including a breech-bolt, a hammer, a main spring, a flexible rod extending through said spring and connected with one end thereof for imparting the force of said spring to the hammer, a connection 20 between the opposite end of the spring and breech-bolt for imparting the force of the spring to the breech-bolt, and means for controlling the movement of the hammer.
- 25 5. A firearm including a breech-bolt, a hammer, hammer actuating means including a movably mounted member, a rod connecting said member with the hammer, said rod being flexible to travel in a curved path with respect to its points of connection to 30 said member and hammer, and means for controlling the movement of the hammer.
- 35 6. A firearm including a hammer, a sear therefor, means including a flexible rod for moving the hammer to firing position, said flexible rod pressing against the sear to move it to engage the hammer, and means for operating the sear.
- 40 7. A firearm including a hammer, a sear therefor, a sear actuating bar to engage the sear, said bar having a cam notch in its edge, a member to yieldingly engage within said notch to cause movement of the bar in one direction, and means for operating the bar in the opposite direction.
- 45 8. A firearm including a breech-bolt, a breech-bolt actuating lever, a breech closing block mounted to resist movement of said lever and having a beveled surface, a resistance block having a beveled surface coöperating with that on the breech closing block, said resistance block being movably mounted to disengage from the breech closing block, and means for firing the firearm to cause movement of the breech-bolt.
- 50 9. A firearm including a breech-bolt, a breech-bolt actuating lever, a main spring, a breech closing block borne by said spring, a lug on the lever resting against said block, the latter having a beveled surface, a resistance block having a beveled surface to engage with that on the breech closing block, said resistance block being movably mounted to disengage from the breech closing block, and means for firing the firearm to cause 60 movement of the breech-bolt.
10. A firearm including a breech-bolt, a breech-bolt actuating lever connected therewith, a lug on the breech-bolt lever, a main spring, a cap seated upon the main spring, a breech closing block secured to the cap and resting against said lug, said breech closing block having a beveled surface, a resistance block having a beveled surface to engage that on the breech closing block, said resistance block being movably mounted 70 for disengagement from the breech closing block, and means for firing the firearm to cause movement of the breech-bolt.
- 75 11. A firearm including a breech-bolt, a breech-bolt actuating lever, a resistance block having a beveled surface to resist movement of said lever, said resistance block being movably mounted to disengage it and permit movement of the lever, means for firing the firearm to cause movement of 80 the breech-bolt in one direction, and means for moving the breech-bolt in the opposite direction.
- 85 12. A firearm including a breech-bolt, breech-bolt actuating means, a member to resist movement of said actuating means, a manually actuated member to engage said actuating means, and means connected with said manually actuated member to disengage 90 said resisting member.
- 95 13. A firearm including a breech-bolt, a breech-bolt actuating lever, means for resisting movement of said lever, a breech-bolt opening lever to engage the breech-bolt actuating lever, and means connected 100 with said opening lever to disengage the lever resisting means.
14. A firearm including a breech-bolt, a breech-bolt actuating lever, means for resisting movement of the lever, a breech-bolt opening lever adapted to engage the breech-bolt actuating lever, and a bar connected with said opening lever and arranged to disengage said lever resisting means.
- 105 15. A firearm including a breech-bolt, a breech-bolt actuating lever, a breech-bolt closing block opposing movement of said lever, a breech-bolt resistance block located in the path of movement of said closing 115 block, a breech-bolt opening lever adapted to engage the breech-bolt actuating lever, and means connected with said opening lever to move said resistance block out of the path of the breech closing block.
- 120 16. A firearm including a trigger guard, a breech-bolt, means to resist movement of the breech-bolt, manually actuated means mounted in accessible position with respect to the trigger guard, and operative connections between said manually actuated means and breech-bolt, also between said manually actuated means and said resisting means.
- 125 17. A firearm including a trigger guard, 130

- a breech-bolt, a breech-bolt actuating lever, means for resisting movement of said lever, a breech-bolt opening lever pivotally mounted underlying said trigger guard and 5 in position to engage the actuating lever, and means connected with said opening lever to disconnect the lever resisting means.
18. A firearm including a hammer, a spring rod secured to the hammer, said rod 10 being flexible to travel in a curved path with respect to its points of connection to other members, a main spring thrusting against said rod to place the hammer under spring action, and means for operating the 15 hammer.
19. A firearm including a frame with a recess therein of angular shape, firing mechanism including a hammer mounted in said recess, a flexible rod located in said 20 recess and operatively connected with the hammer, and a main spring located in said
- recess and operatively connected with the opposite end of the rod, the angular portion of said recess intersecting a straight line between the points of connection for 25 the opposite ends of said rod.
20. A magazine for a firearm, a follower for said magazine, means for forcing the follower in one direction, the edges of the magazine having depressions therein forming a curved chamber within the magazine. 30
21. In a firearm, a breech-bolt, a breech-bolt actuating lever, a U-shaped pivotally mounted opening lever connected with the breech-bolt lever, and a pin of angular 35 shape in cross section engaging the opposite sides of said opening lever and forming the pivot thereof.

GRANT HAMMOND.
